UNITED STATES PATENT OFFICE.

DANIEL F. LEPLEY, OF CONNELLSVILLE, PENNSYLVANIA.

HOIST MECHANISM.

Application filed October 22, 1921. Serial No. 509,650.

To all whom it may concern:

Be it known that I, DANIEL F. LEPLEY, a citizen of the United States, residing at Connellsburg, in the county of Fayette and State of Pennsylvania, have invented a new and useful Hoist Mechanism, of which the following is a specification.

This invention relates to hoisting mechanism for use in actuating mine cages and the like and it is designed more particularly as an improvement upon the structure disclosed in my Patent 1,419,155, dated June 13th, 1922.

In the construction referred to there are employed rods connected to a rack bar receiving motion through suitable mechanism from a winding drum so that when the operated cage approaches one of its limits of movement the operation of the parts will 20 be gradually slowed down and finally brought to a stop. As a part of the mechanism for this purpose one of the rods actuated by the drum driven mechanism is provided with projections whereby either 25 one of opposed stop arms are actuated for the purpose of automatically shifting the controlling lever or levers of the hoist mechanism to neutral position, to slow down and stop the operation of the mechanism.

It has been found in mechanism such as heretofore described and as disclosed in my application mentioned that where there is a short hoist the button or projection used for shifting the stop arm will sometimes come 35 to a stop under the arm. Consequently if the cage has stopped slightly below or above the landing stage it has not been possible to operate the controlling lever or levers by hand in order to move the cage to exact position.

It is an object of the present invention to improve upon the mechanism hereinbefore described by providing stop arms which will operate as heretofore but which, nevertheless, will allow the controlling lever or levers 45 to be shifted slightly against the arms and sufficiently to start the hoisting mechanism so as to bring the cage to the proper level.

With the foregoing and other objects in view which will appear as the description proceeds, the invention resides in the combination and arrangement of parts and in the details of construction hereinafter described and claimed, it being understood 50 that, within the scope of what is claimed,

changes in the precise embodiment of the invention shown can be made without departing from the spirit of the invention.

In the accompanying drawings the preferred form of the invention has been shown. 60

In said drawings—

Figure 1 is a side elevation of that portion of hoisting apparatus constituting the present invention and showing the yielding stop arms in position relative to a controlling 65 lever.

Figure 2 is an enlarged side elevation of one of the stop arms, parts being shown in section.

Figure 3 is a front elevation thereof, the 70 roller being removed.

Figure 4 is a plan view, the roller being removed.

Figure 5 is a side elevation of a portion of hoisting mechanism having the present invention combined therewith, the upper portion of the front lever being broken away to disclose the upper portion of the rear or controller lever. 75

Figure 6 is a side elevation of another 80 portion of said mechanism.

Figure 7 is a section on line 7—7, Figure 1.

Referring to the figures by characters of reference 15 designates pedestals or chairs on which a rod 14 is mounted to slide, this 85 rod being connected to a cross head 13 mounted on and movable with a rack bar 10 forming part of the hoisting mechanism disclosed in my application before mentioned. Another rod 29 is pivotally connected to the bar 10 and slidably engages the lower end portion of a controlling lever 26 which is fulcrumed at 28, there being cushioning springs 31 and 32 on the rod at 90 opposite sides of the lever but which constitute in themselves no part of the present invention. 95

Pins 20 are carried by the upper portions of the chairs or pedestals 15 and mounted on each of these pins is a bell crank lever including a stop arm 21 and a tripping arm 22. A roller 23 is carried by each tripping arm, this roller being mounted on a pin 52 which is slidable within a slot 53 formed in the tripping arm. A yoke 54 straddles the arm 22 and has a stem 56 extending therefrom and slidably within a tubular guide 57. This guide is exteriorly screw threaded and is secured within an ear 58 100 extending from the arm 21, there being a nut 105 110

59 for locking the member in position. A spring 60 is mounted on the rod 56 and bears at one end against the yoke 54 and at its other end against the guide member 57.

5 As shown in Figure 1 one of the arms 21 is disposed directly opposite the other and both arms have offset portions 24 extending toward each other and terminating in heads 25. Projections or buttons 17 are secured on the rods 14 and are adapted to work under the rollers 23.

10 The mechanism thus far described and which constitutes the present invention is to be used in connection with hoisting mechanism such as shown generally in Figures 5 and 6 and more specifically set forth for example in my patents issued on June 13th, 1922, numbered 1,419,154 and 1,419,155. This hoisting mechanism includes broadly a drum 1 adapted to transmit motion through a train of gears 2 to a shaft 3. Gears 4 and 5 transmit motion from this shaft to a shaft 6 on which is mounted a worm 9 designed to mesh with the rack bar 10 hereinbefore referred to. The lever 27 for controlling the motor M which actuates the drum 1 is connected to a controller C by means of a link 27'. The lever 26 which controls the brake is designed to operate suitable valve mechanism 70 of an engine E, this engine and its valve mechanism constituting in itself no part of the present invention but being utilized solely as a means whereby the lever 71 which is coupled through the rod 72 and bell crank 73 with the brake bands or shoes 74 will be actuated to apply the brake when the lever 26 is brought to its neutral position.

15 During the operation of the hoisting mechanism the lever 26 is out of neutral position as shown in Figure 1 and the rod 14 is moved slowly in the direction indicated by the arrow, this movement being produced by the shifting of the rack 10 due to the rotation of the worm 9. The parts are so timed that when the cage approaches the landing the button 17 shown to the left in the illustration will come under the near roller 23 and thrust upwardly through the spring 60 against the ear 58, thereby causing the arm 21 to push against lever 26 and throw it to neutral position. As the mechanism indicated in Figure 1 is provided not only for the lever 26 but also for the lever 27 (the rods 29 and 14 for the two levers being shown in section in Figure 7) it will be apparent that lever 27 will at the same time be shifted so as to cut off the current to the motor. In a short hoist the button 17 is liable to stop directly under the roller 23 with the hoisting mechanism at a standstill. If at this time the cage should be slightly below the landing it would of course be necessary to momentarily operate the hoisting mechanism in order to raise the cage the necessary distance. To do this the

operator pulls on the upper end of lever 26 so as to force the lower end thereof against the head 25 engaging it. Thus the ear 58 will press downwardly on spring 60 and place the spring under compression, the movement of the lever being sufficient to start the mechanism of the hoist and as soon as the cage has reached the exact level desired the lever can be released and moved to neutral position. Thus it will be seen that by providing the improvement herein described there is no danger of the hoisting mechanism stopping and becoming locked before the cage reaches the exact level desired. In this connection it might be stated that a hoist of this character operates the cage at a speed of about 2,000 feet per minute and five seconds are allowed for bringing it to a stop, the cage slowing and stopping within sixty feet. As the loads on the cage vary from 3,500 pounds to 6,500 pounds and the momentum correspondingly varies, the hoist rarely if ever stops at the same point. By providing the mechanism herein described no difficulty will be experienced in bringing the cage to the proper level quickly and accurately after being brought to an automatic stop.

What is claimed is:-

1. In hoisting mechanism the combination with a controlling lever, of tiltable stop devices at opposite sides of the lever, slidable means for actuating either of the stop devices to shift the lever to neutral position and yielding means for holding the stop devices against movement. 95

2. In hoisting mechanism the combination with a controlling lever, of yieldable stop devices tiltably mounted and at opposite sides of the lever, and movable means for actuating either of the stop devices to shift the lever to its neutral position. 105

3. In hoisting mechanism the combination with a controlling lever, of opposed tiltable stop devices for actuation of the lever, a spring controlled roller movably connected to each of the stop devices, and movable means for engaging either roller to force either stop device against the controlling lever to move said lever to neutral position. 110

4. In hoisting mechanism the combination with a controlling lever, of opposed stop devices tiltably mounted at opposite sides of the lever, each stop device including a bell crank, a stop head on one arm of the bell crank, a yoke slidably mounted on the other arm of the bell crank, yielding means for controlling the movement of the yoke relative to the bell crank, a roller movable with each yoke, and slidable means movable against the respective rollers to actuate the respective stop devices and shift the lever to neutral position from either extreme position. 125 130

5. A mechanical automatic controlling mechanism for a power operated hoist including a power control means, a retarding means, and slideable hoist operated shifting means, said slideable shifting means cooperating, first, with the power control means to successively bring it to hoist stopping position and to release it, and, second, with the hoist retarding means to gradually shift 10 it to position to bring the hoist to a gradual and safe stop at a predetermined point short of its ultimate terminus, if not interfered with, and yielding means to permit

the operator to retain sufficient manual control to bring the hoist slowly to its final 15 terminus.

6. In hoist mechanism a controlling lever, yieldable stop devices at opposite sides of the lever, and means for actuating either of the stop devices to shift the lever to its 20 neutral position.

In testimony that I claim the foregoing as my own, I have hereto affixed my signature.

DANIEL F. LEPLEY.
